ENGINE

Humbert Denis Jean Cantoni, Paris, France, assignor to Mawen S. A., Paris, France, a stock company of France

Application May 11, 1938, Serial No. 207,211
In France August 9, 1937.

12 Claims. (Cl. 123—171)

The present invention relates to internal combustion air cooled engines and has particular reference to air cooled engines of the kind in which a series of banks of radially arranged cylinders are placed in line, one behind another. Still more particularly the invention relates to the above described kind of engine in which both the cylinder banks and the crankshaft revolve, usually in opposite directions, and control of gas flow from the engine cylinders is effected by means of annular valve structure surrounding the several cylinder banks. Such engines may for convenience be generically referred to as bi-rotary engines.

In the case of a single bank engine, adequate cooling of the cylinders can usually be effected by the circulation of air resulting from the rotary movement of the cylinder bank and in some instances adequate cooling can be effected by the rotary movement alone in the case of a two bank engine, particularly where such engine is used for aircraft propulsion and is subjected to a strong blast of air from the slip stream of the propeller.

In cases where more than two banks are employed, it is difficult, if not impossible, to effect adequate cooling, particularly in cases where engines of this sort may be employed for the propulsion of motor cars or the like.

The present invention has for its general object the provision of improved cooling structure for engines of the kind under consideration, which structure permits by simple and effective means, adequate cooling of all of as large a number of banks of cylinders as it may be desired to employ.

The manner in which the above general object and other and more detailed objects of the invention may be accomplished will best be understood from a consideration of the ensuing portion of this specification, taken in conjunction with the accompanying drawings forming a part thereof in which:

Fig. 1 is a diagrammatic representation of an engine constructed in accordance with the general principles of the invention;

Fig. 2 is a section taken on the line 2—2 of Fig. 1;

Fig. 3 is a section illustrative of a commercial design of engine embodying the invention; and

Fig. 4 is a section taken along the line 4—4 of Fig. 3.

Fig. 5 is a diagrammatic longitudinal section taken along the line 5—5 of Fig. 6, of a further embodiment of the invention;

Fig. 6 is a transverse section taken along the lines 6—6 of Figs. 5 and 7;

Fig. 7 is a partial plan view, corresponding to Figs. 5 and 6.

5 Referring now to the diagrammatic illustrations of Figs. 1 and 2, the engine illustrated comprises a series of four banks 12, 14, 16, and 18 respectively, of radially arranged cylinders 10 fixed at their inner ends to a crank case structure indicated generally at 20 and mounted to revolve about a common crankshaft 22 which is also revolvably mounted and adapted, in the embodiment illustrated, to drive a propeller 24. Around the motor assembly there is provided the rotationally stationary housing 26 having at its forward end a series of air inlet ports 28 and a series of lateral air inlet openings 30 between the successive cylinder banks. Over these openings there are preferably provided a series of projecting scoops 32 opening in the direction of movement of the engine relative to the flow of air thereover. At the rear of the surrounding casing there are provided air exhaust openings 34 and between these openings and the last cylinder bank there is provided a suction fan 36 which in the embodiment illustrated is a high speed propeller type fan driven through planetary gearing comprising a gear 38 connected to the crankshaft 22, planet gears 40 mounted on pins 42 fixed in the housing and an internal ring gear 44 forming a part of the fan structure.

20 In the embodiment illustrated in Figs. 3 and 4 a practical application of the invention is shown more fully.

25 In the invention shown in this embodiment the outer stationary structure is indicated generally at 50 and within this structure there is rotatably mounted the crankshaft 52 to which is attached at one end a suitable flywheel 54. At the opposite end the crankshaft is advantageously splined as at 56 for fixing thereto a propeller if the engine is to be used for aircraft purposes. In an automobile installation, drive will ordinarily be taken from the flywheel end of the crankshaft.

30 The shaft illustrated is provided with four crank pins 60, 62, 64, and 66 to which, respectively, are attached the connecting rods 68, 70, 72, and 74 of the four banks of radially arranged cylinders 76, 78, 80, and 82.

35 The cylinders of the several banks are attached at their inner ends to a common crank case structure indicated generally at 84, which structure is rotatably mounted both with respect to the crankshaft and the stationary structure 50. Forming a part of the stationary structure

of the engine is an annular barrel-like member 86 encircling the several banks of cylinders and constituting among other things a ported valve for controlling admission and exhaust of gases from the several cylinders. The inner surface of this valve member is ground to provide a series of concave spherical tracks or valve sealing faces 88, 90, 92, and 94, one for each bank of cylinders. The outer ends of the cylinders are formed with neck portions 96 providing cylindrical surfaces in which are slidably mounted sealing members 98 having spherically curved outer flanges 100 at their outer ends adapted to seat against their cooperating spherically curved valve surfaces to provide seals for the combustion gases. At suitably spaced intervals peripherally of each bank, the valve member is ported as indicated at 102 for connection to either intake or exhaust manifold as the case may be.

The outer surface of the valve member is advantageously provided with a series of longitudinally disposed radially projecting cooling fins 104 and between the several spherically curved valve tracks, the valve member is provided with a series of rows of air inlet ports 106, 108, and 110. As will be clear from Fig. 4, these ports are distributed around the periphery of the structure, and they are advantageously staggered with respect to the port openings to which the various manifold connections are made.

Relative rotation between crankshaft, stationary valve structure, and cylinder banks is obtained by means of crankshaft gear 112 connection by means of suitable chain drive to gear 114 on lay shaft 116 mounted in the stationary structure 50. The lay shaft 116 is provided with a second gear 118 meshing with gear 120 fixed to the rotating crank case structure 84. Since gears 112 and 114 rotate in the same direction while gears 118 and 120 rotate in opposite directions, it will be evident that the crankshaft and cylinder assemblies rotate in opposite directions and both rotate in fixed timed relation to the stationary structure. In the embodiment illustrated, an annular intake manifold 122 is provided which is connected to the carburetor outlet diagrammatically indicated at 124. From this annular inlet manifold a series of longitudinally extending branch connections, one of which is indicated generally at 126, extend along the outside of the valve member for connection to the several inlet ports. The details of such connection and of the manifolding for the exhaust ports are not essential to an understanding of the present invention and for clearness of illustration these parts have been omitted from the drawing.

At the flywheel end of the engine the casing structure 50 is advantageously shaped to form a volute casing 128 providing a passage in communication through suitable openings 130 with the space in which the cylinder banks rotate. Within this volute casing a turbo fan 132 is provided, which may advantageously be formed as a part of the flywheel 54. Fan 132 discharges through suitable outlet ports 134 in the stationary structure.

Advantageously, the walls of the stationary valve member 86 behind the several air admission ports are curved forwardly as indicated at 136 to provide scooplike openings for directing the air admitted through the several ports in radially inward direction and in addition the stationary structure is advantageously provided at its

forward end with openings for admission of air such as are indicated at 158. The manner in which the structure accomplishes the object sought to be obtained will be largely apparent from the drawings. Due to the openings spaced longitudinally along the casing, fresh and comparatively cool air is drawn in in front of each of the individual cylinder banks to provide for efficient cooling of each bank and the distribution of the air inlets along the length of the engine, combined with the turbulence resulting from the rotary movement of the cylinders within the casing, insures even and adequate cooling for the several cylinder banks regardless of the number of such banks employed.

According to the modification of Figs. 5 to 7, the engine illustrated comprises a series of four banks 140, 142, 144, and 146, respectively of radially arranged cylinders 148 fixed at their inner ends to a crank-case structure indicated generally at 150 and mounted to revolve about a common crank-shaft 152 which is also revolvably mounted and adapted to drive, in the embodiment illustrated, a propeller 154. Around the engine assembly there is provided a rotationally stationary casing structure 156 having at its forward end a series of air inlet openings 158 and at its rearward end a series of air exhaust openings 160.

Forming a part of the stationary casing structure 156 is an annular barrel-like member 162 encircling the several banks of cylinders and constituting among other things a ported valve for controlling admission and exhaust of gases from the several cylinders. The inner surface of this valve member is ground to provide a series of concave spherical tracks or valve sealing faces 164, 166, 168 and 170, one for each bank of cylinders. The outer ends 172 of the cylinders are formed in a manner similar to that illustrated in Fig. 3 and not shown in Figs. 5 and 6, with neck portions in which are slidably mounted sealing members adapted to seat against their cooperating spherically curved valve surfaces to provide seals for the combustion gases. At suitably spaced intervals peripherally of each bank, the valve member is provided with admission ports 174 and exhaust ports 176, and with ignition plugs 178.

Relative rotation between crankshaft, stationary valve structure and cylinder banks is obtained by means not shown, similar to those illustrated in Fig. 3.

In the cylindrical wall of the valve member 162 are provided air passages 180 opening at 182 on to the front end of this valve member. The passages 180 are ported at 184, 186, 188 and 190 to provide communication with the interior of the casing structure, the ports 184, 186, 188 being located between each two adjacent cylinder banks and the port 190 being located behind the rear cylinder bank. The passages 180 are also ported at 192, 194 and 196 to provide communication with the exterior of the valve structure. The ports 192, 194 and 196 are slightly displaced towards the rear with respect to ports 184, 186 and 188, respectively, and their rear edges are provided with scooplike projections 198, 200 and 202.

Between the rear openings 160 in the casing structure and the last cylinder bank there is provided a suction fan 204 driven through planetary gearing comprising a gear 206 connected to the

crankshaft 152, planet gears 208 mounted on pins 210 fixed in the casing structure and an internal ring gear 211 forming a part of the fan structure.

It will thus be appreciated that fresh and cool air is drawn in through the front air inlet openings 158 and 182 and through the peripheral ports 192, 194 and 196. The air circulating within the passages 180 enters the casing structure through ports 184, 186, 188, and 190 and provides for efficient cooling of each bank.

To provide also for efficient cooling of the portions of the casing adjacent the ignition plugs, the admission gases coming from the admission manifold not shown are led to the admission ports 174 in the valve member 162 through passages 212 provided in the wall of the valve member and surrounding at 213 the ignition plugs 178. The comparatively cool admission gases thus cool the portions of the casing adjacent the ignition plugs. Besides the cooling thus obtained this arrangement is of advantage since the admission gases are preheated and their thermic atomization is enhanced before they are introduced into the cylinders.

It will be evident to those skilled in the art that the invention may be embodied in many different specific forms of engine structure which may vary considerably from the structure illustrated by way of example, without departing from the scope of the invention. While a suction fan is to be preferred, it will be evident that a blast fan may be employed to cause forced circulation by producing positive rather than negative pressure within the casing.

The invention is accordingly to be understood as embracing all forms of apparatus falling within the scope of the appended claims.

What is claimed is:

1. A multiple bank bi-rotary engine comprising a series of banks of rotatably mounted radially arranged cylinders, said banks being arranged one behind another, a stationary casing structure encircling said banks and including a ported valve member providing a series of ported valve tracks, one for each bank, means carried at the outer ends of the several cylinders and cooperating with the ports in said valve tracks to provide for flow of cylinder gases, and a series of air admission ports formed in said valve member, the last mentioned ports being arranged to admit air to the interior of the casing structure through portions of the valve member located longitudinally between said valve tracks.

2. A multiple bank bi-rotary engine comprising a plurality of rotatably mounted banks of radially disposed cylinders, said banks being arranged one behind another, a stationary casing structure including a valve encircling said cylinder banks and having a series of annular ported valve tracks, means carried at the outer ends of the cylinders and cooperating with the ports in said valve tracks to control flow of cylinder gases, and a series of air admission ports peripherally distributed around said valve member and located longitudinally between the several valve tracks, said valve member being shaped adjacent to said air admission ports to provide scoop-like projections for directing air inwardly from the exterior to the interior of the casing structure.

3. A multiple bank bi-rotary engine comprising a series of banks of rotatably mounted radially arranged cylinders, a casing structure encircling said banks and including a valve member providing a series of valve tracks, one for each bank, said valve tracks being provided with admission

and exhaust ports and with ignition means, means carried at the outer ends of the several cylinders for flow of cylinder gases, a series of peripherally spaced longitudinal air passages provided in the walls of said valve member, each of

5 said air passages having an air inlet opening located on the front face of said casing structure, a series of lateral air outlet ports for flow of air from said air passages into said casing structure and located longitudinally between the several banks and at the rear of the last bank and a series of air inlet ports for admitting air from the exterior into said air passages, one of said air inlet ports being provided slightly at the rear of each of air outlet ports which are located longitudinally between the several banks.

4. A multiple bank bi-rotary engine comprising a series of banks of rotatably mounted radially arranged cylinders, a casing structure encircling said banks and including a valve means providing 20 a series of valve tracks, one for each bank, said valve tracks being provided with admission and exhaust ports and with ignition means, means carried at the outer ends of the several cylinders for flow of cylinder gases, a series of peripherally spaced longitudinal air passages provided in the walls of said valve member, each of said air passages having an air inlet opening located on the front face of said casing structure, a series of lateral air outlet ports for flow of air from said air passages into said casing structure and located longitudinally between the several banks and at the rear of the last bank and a series of air inlet ports for admitting air from the exterior into said air passages, one of said air inlet ports being provided slightly at the rear of each of the air outlet ports which are located longitudinally between the several banks, said valve member being shaped adjacent to said air inlet ports to provide scoop-like projections for directing air invariably from the exterior to the interior of said air passages.

5. In a multiple bank engine of the character described, a valve member of generally cylindrical annular form having a plurality of longitudinally spaced circular valve tracks formed on its inner surface, different tracks being located to cooperate with the cylinders of different banks, a series of passages formed in said member for flow of cylinder gases, said passages terminating in ports opening at peripherally spaced intervals through said valve tracks, and a plurality of passages extending through the valve member for flow of cooling air from the exterior to the interior of the valve member, the last named passages communicating with the interior of the valve member at peripherally spaced places located longitudinally intermediate each two adjacent valve tracks.

6. In a multiple bank engine of the character described, a valve member of generally cylindrical annular form having a plurality of longitudinally spaced circular valve tracks formed on its inner surface, different tracks being located to cooperate with the cylinders of different banks, a series of passages formed in said member for flow of cylinder gases, said passages terminating in ports opening at peripherally spaced intervals through said valve tracks, a plurality of passages extending through the valve member for flow of cooling air from the exterior to the interior of the valve member, the last named passages communicating with the interior of the valve member at peripherally spaced places located longitudinally intermediate each two adjacent valve tracks.

7. In a multiple bank engine of the character described, a valve member of generally cylindrical annular form having a plurality of longitudinally spaced circular valve tracks formed on its inner surface, different tracks being located to cooperate with the cylinders of different banks, a series of passages formed in said member for flow of cylinder gases, said passages terminating in ports opening at peripherally spaced intervals through said valve tracks, a plurality of passages extending through the valve member for flow of cooling air from the exterior to the interior of the valve member, the last named passages communicating with the interior of the valve member at peripherally spaced places located longitudinally intermediate each two adjacent valve tracks.

cent valve tracks, and air scoop means formed on the exterior of said valve member for directing air into the last mentioned passages.

7. In a multiple bank engine of the character described, a valve member of generally cylindrical annular form and having a plurality of longitudinally spaced valve tracks formed on its inner surface, different tracks being located to cooperate with the cylinders of different banks, passages extending through said valve member and terminating in ports opening into the valve tracks for flow of cylinder gases, and a plurality of longitudinally extending passages peripherally offset with respect to the valve port passages, said longitudinally extending passages having longitudinally spaced openings communicating with the interior of the valve member at places longitudinally intermediate said valve tracks and having openings for admission of air to the passages.

8. In a multiple bank engine of the character described, a valve member of generally cylindrical annular form and having a plurality of longitudinally spaced valve tracks formed on its inner surface, different tracks being located to cooperate with the cylinders of different banks, passages extending through said valve member and terminating in ports opening into the valve tracks for flow of cylinder gases, and a plurality of longitudinally extending passages peripherally offset with respect to the valve port passages, said longitudinally extending passages having longitudinally spaced openings communicating with the interior of the valve member at places longitudinally intermediate said valve tracks and having openings longitudinally spaced along the length of the passages for admitting air thereto.

9. In a multiple bank engine of the character described, a valve member of generally cylindrical annular form having a plurality of longitudinally spaced valve tracks formed on its inner surface, different tracks being located to cooperate with the cylinders of different banks, a series of peripherally spaced inlet ports in each of said tracks, a series of inlet manifold passages formed in said member, said passages being peripherally spaced and extending longitudinally of the valve member from an end thereof to communicate with inlet ports in at least two of said valve tracks, and a plurality of exhaust passages in said member, said passages providing a series of peripherally spaced exhaust ports for each valve track, the exhaust passages being peripherally spaced from each other and being peripherally spaced from and alternating with said inlet manifold passages.

10. In a multiple bank engine of the character described, a valve member of generally cylindrical annular form having a plurality of longitudinally spaced valve tracks formed on its inner surface, different tracks being located to cooperate with the cylinders of different banks, a series of peripherally spaced inlet ports in each of said tracks, a series of ignition openings for the reception of ignition means in each of said tracks, said openings being peripherally spaced from each other and from the inlet port openings in the same track, a series of peripherally spaced inlet manifold passages formed in said

member, each of said passages having an inlet opening at an end of the valve member and extending longitudinally of the valve member around the ignition openings in at least two of said tracks and communicating with inlet ports in the same valve tracks, and a series of exhaust passages in said member, said exhaust passages being peripherally spaced from each other and from said inlet manifold passages and communicating with a series of peripherally spaced exhaust ports in each of said valve tracks.

11. In a multiple bank engine of the character described, a valve member of generally cylindrical annular form having a plurality of longitudinally spaced valve tracks formed on its inner surface, different tracks being located to cooperate with the cylinders of different banks, a series of peripherally spaced inlet ports in each of said tracks, a series of inlet manifold passages formed in said member, said passages being divided into different groups, the passages of each group being peripherally spaced and the passages of one group having inlets at one end of the valve member and the passages of the other group having inlets at the other end of the valve member, said passages extending longitudinally toward the center of the valve member from the ends thereof and each passage communicating with inlet ports in at least two of said valve tracks, and a series of exhaust passages in said valve member, said exhaust passages providing a series of peripherally spaced exhaust port openings in each of said valve tracks and being peripherally spaced with respect to said inlet manifold passages.

12. In a multiple bank engine of the character described, a valve member of generally cylindrical annular form having a plurality of longitudinally spaced valve tracks formed in its inner surface, different tracks being located to cooperate with the cylinders of different banks, a series of peripherally spaced inlet ports in each of said tracks, a series of ignition openings for the reception of ignition means in each of said tracks, said openings being peripherally spaced from each other and from the inlet port openings in the same track, a plurality of inlet manifold passages formed in said member, said passages being divided into different groups, the passages of each group being peripherally spaced and the passages of one group having inlets at one end of the valve member and the passages of the other group having inlets at the other end of the valve member, said passages extending longitudinally toward the center of the valve member from the ends thereof, each passage extending to communicate with inlet ports in at least two of said valve tracks and each passage having a portion surrounding an ignition opening in each of the valve tracks with which it provides communication with an inlet port, and a series of exhaust passages in said member, said exhaust passages providing a series of peripherally spaced exhaust ports in each valve track and being peripherally spaced with respect to each other and said inlet manifold passages.

HUMBERT DENIS JEAN CANTONI.
